DUNCAN L. McCORKINDALE, OF HOLYOKE, MASSACHUSETTS.

METHOD OF AND MEANS FOR MAKING PAPER.

1,147,331.

Specification of Letters Patent. Patented July 20, 1915.

Application filed January 2, 1915. Serial No. 113.

To all whom it may concern:

Be it known that I, DUNCAN L. McCORKINDALE, a citizen of the United States of America, residing at Holyoke, in the county of Hampden and State of Massachusetts, have invented a new and useful Method of and Means for Making Paper, of which the following is a specification.

My invention relates to improvements in methods of decreasing the thickness of a web of paper, during its manufacture from the pulp and in the paper-making machine, whereby such web shall have produced therein one or more sections or channeled portions which are thinner than the adjacent sections or portions. Paper so thinned or channeled is particularly useful for the leaves of books, such books as those of the ledger type for example, whether such leaves be detachable or not, although not restricted to such use. In order that the leaves of a book, which leaves consist of fairly thick paper, may be readily turned when the book is opened, shall be flat when open, and will occupy less space or thickness at the bend, each of such leaves should be made thinner adjacent to its binding edge, wherefore the aforesaid channeled portions or channels are so arranged in the web as to enable the latter to be cut into leaves each of which has a thin portion extending along a course that is parallel with and adjacent to such binding edge.

My invention consists in a method of producing paper, of the character just described, by compressing with mechanical means portions of the web while in a pulpy state on the Fourdrinier or cylinder and at the same time removing by mechanical means and gravity such portions or particles of the pulp web as are not pressed into said web by the action of said first-mentioned means, whereby a portion of said web is channeled in a straight course and in means, comprising a hollow perforated wire-covered rotary member provided with interior buckets, a receptacle, trough or funnel over which such buckets are carried and into which they empty, and a conduit or conduits leading from said receptacle or funnel, for carrying said method into effect, all as hereinafter set forth.

More broadly considered or expressed, perhaps, the method may be said to consist in simultaneously compressing in part and

removing in part a portion of the thickness of the web along and between lines extending longitudinally of said web.

As a preliminary step to the foregoing method and a step therefore in an amplification of my method, some of the pulpy material is dispersed prior to compressing and removing what remains. In other words, a shallow straight path or track is made in the web, such track being made by subjecting the moving web to a fixed member which dips down into and disperses a portion of the same, so as to present a thinner portion of the web to the compressing and removing agency. And the means for thus dispersing the pulp and forming the initial track also enters into the mechanical part of my invention. Without this preliminary step there may be danger, when the pulp is thick and possesses certain characteristics, that a sufficient amount will not be removed at the time the compression takes place, in consequence of which the thickness to be compressed is too great, and in that event the fibers are crushed by the compression and the channeled portion has a mottled appearance and its texture is impaired.

The primary object of my invention is to provide a practical method of and comparatively simple yet highly efficient mechanism or means for producing paper which can be cut into sheets that have marginal and body portions connected by thin portions.

A further object is to provide such a method that can be carried out with the aid of or in connection with an ordinary paper-making machine of either type, and such means that are adaptable and applicable to and capable of being readily and practically incorporated with such a machine.

Other objects and advantages will appear in the course of the following description.

The invention is illustrated with the aid of and in the accompanying drawings, in which—

Figure 1 is a front elevation of mechanism which embodies a practical form of the mechanical part of my invention as applied to a Fourdrinier machine, one of the adjusting sleeves being in section, portions of the tubular rod being broken out, and portions of the wheel covering and wheel rim being broken away; Fig. 2, a top plan

of the channeling mechanism, including the tracker or spreader; Fig. 3, a section taken through the axial center of the combined displacing or compression and conveying member or wheel, together with the supporting and associated parts; Fig. 4, an end elevation of said mechanism, the tubular rod being in section; Fig. 5, a top plan, on a reduced scale, of said mechanism and of such portions of the Fourdrinier machine as are illustrated in the first view, showing the results of the operation of such mechanism, and, Fig. 6, a detail in end elevation showing the manner in which said tubular rod is supported in raised position.

15 Similar numerals refer to similar parts throughout the several views.

Before referring specifically to the drawings, it may be stated that in detail the 20 method, for the putting into effect of which the mechanism illustrated in said drawings is provided, consists in moving a web of paper material, while in a plastic condition on the wire of an ordinary Fourdrinier machine, or on the cylinder of an ordinary cylinder machine, first under one or more dispersing members set to produce a corresponding number of shallow paths or tracks in such material, and then under the same 25 number of rotatably mounted members so arranged as to displace or compress such material, along the paths or tracks already formed therein, and so constructed as at the same time to remove by contact and convey 30 away portions of such material from the same paths or tracks, whereby the portions of said web thus acted on by said members are left thinner than the body part outside of the lines of action of said members, and thinner than the initial track portions. The 35 web, after being channelled in the manner and by the method just explained, passes over a suction-box, usually the first suction-box, and thence onward to completion the 40 same as though my new method had not been added to the paper-making process. Additional details of the method will be explained in connection with the following 45 description of the mechanism.

50 The mechanism for carrying out the new process or method comprises a movable hollow drum or wheel 1 having a multiplicity of slots, holes or openings 2 in the periphery or rim, and provided on the inside of such 55 rim with a plurality of buckets 3, and on the outside of such rim with a wire covering 4, and a funnel 5 arranged within said wheel beneath the circular path described by said buckets as the wheel revolves, together with 60 supporting and adjusting means for said wheel and conduits leading from said funnel, which will subsequently be described in detail. A tracker or spreader 6 is also included in the aforesaid mechanism, and this 65 also will be described subsequently in detail.

The wheel 1 is mounted in such a manner, relative to the pulp-carrying member of the paper-making machine with which the channeling mechanism is incorporated, that the pulp as it is carried under said wheel 70 is crowded together or made thinner than the pulp that passes on both sides of the wheel periphery at successive points of contact with said pulp, said wheel being rotated by reason of its contact with the moving 75 pulp. This thinning process could not be successfully carried out and the desired result produced, however, without making provision for the removal of a portion of the pulp along the course of the channel, 80 and to this end the openings or perforations 2 and the buckets 3 are provided, the particles adhering to and taken up by the wire surface 4 of the wheel and a portion of the displaced fibrous material escaping between 85 the wires of said surface or covering and through said perforations and being received in said buckets which deliver them to the funnel 5. The surface of the wheel 1 which contacts with the pulp must necessarily be of wire, either woven or spirally wound, for reasons which are well understood by those skilled in the paper-making art, and such surface naturally picks up 90 some of the fibrous or pulpy material, and this together with any of such material that is in excess of the amount that can successfully be packed together in the formation of the bottom of the channel or might possibly be displaced laterally is removed from 95 the paper-making field in the manner and by the means just explained, at the same time that the packing or compressing operation takes place. The same means also prevents, of course, the accumulation of pulp on 100 the wire periphery of the wheel, which accumulation would be fatal to the successful 105 operation of the mechanism.

The covering 4 which I have shown consists of wire spirally wound on the wheel 110 rim, but such covering may be of a similar nature to the covering or outer surface of a dandy-roll.

The buckets 3 are arranged so that the entrance thereto or the openings into their 115 pockets are behind in the direction of rotation of the wheel 1, like buckets in any ordinary rotary conveyer.

The wheel 1 has a hub 7, and this is loosely mounted on a sleeve 8, which in turn 120 is fixedly mounted on a tubular support or hollow rod 9 having a longitudinal slot 10 in the top thereof. The hub 7 is held against endwise movement on the sleeve 8 between and by means of an external shoulder 11 on said sleeve and a collar 12, said collar being mounted on said sleeve and secured thereto by a thumb-screw 13 that is tapped into said hub and with its inner end 125 engages said sleeve. The sleeve 8 is held 130

against endwise movement on the rod 9 by means of thumb-screw 14. The thumb-screw 14 is tapped into the sleeve 8 and engages with its inner end the rod 9. Upon 5 loosening the thumb-screw 14, the sleeve 8 with the wheel 1 can be moved to any required point on the rod 9, when said thumb-screw is retightened. Thus the wheel 1 is 10 adjusted so as to locate the channel to be formed thereby in the web the required distance from the adjacent edge of such web or from the adjacent channel to be formed by another wheel. The hollow stem 15 of the funnel 5 is tapped into and through the top 15 of the sleeve 8, and projects downward into and through the slot 10 in the rod 9, which slot is provided to enable the parts to be adjusted longitudinally of said support.

The waste material is delivered to the 20 funnel 5 by the buckets 3 as they pass over said funnel, such material dropping out of the same into said funnel, and passes down through the stem 15 into the passage 16 in the rod 9, from whence it is conveyed away, 25 usually escaping from one or both ends of said passage.

Besides making provision for the lateral adjustment of the wheel 1, it is necessary to provide for adjusting said wheel to and 30 from the pulp-carrying member, in order to produce a channel of the required depth. For this purpose I employ saddle bearings 17-17, in which to mount the rod 9, and provide these bearings with externally 35 screw-threaded depending stems 18-18 which are received in internally screw-threaded sleeves 19-19 having top flanges 20-20. Sections of the frame of a Fourdrinier frame are represented at 21-21, and 40 the sleeves 19 are arranged in vertical openings in such frame sections with their flanges 20 resting on the upper surfaces of said sections. Thus the bearings 19 are supported by and above the frame of the 45 machine. The flanges 20 have radial openings 22 therein to receive a rod with which to turn or rotate said flanges and the sleeves 19. By rotating the sleeves 19 in one direction or the other the stems 18 and the 50 bearings 17, with the rod 9 and the parts mounted on and supported by said rod, including the wheel 1, are lowered or raised accordingly, and said wheel is positioned nearer to or farther from the pulp-carrying 55 member, which in the present case is a Fourdrinier wire. A section of the aforesaid wire is represented in Fig. 5, and a fragment in each of Figs. 1 and 4, at 23.

A pair of pins 24 may be provided with 60 which to secure the rod 9 immovably to the bearings 17, such pins passing through transverse openings in said rod and bearings, as best shown in Fig. 5. When it is desired to support the channeling mechanism well above the wire 23 and entirely

clear of the pulp if any on said wire, for the purpose of lateral adjustment of the parts, or for any other reason, the pins 24 are withdrawn, the rod 9 is raised high enough to enable said pins to be reinserted 70 in the bearings 17, which is done, and said rod is then permitted to rest on said pins—see Fig. 6. The rod 9 is relocated in the crotches of the bearings 17, after the required lateral adjustment has been made, or 75 when all is in readiness for operation.

In Figs. 1, 4 and 5 a portion of a web of pulpy paper material is represented at 24. The channel being formed by the wheel 1 in Figs. 1 and 4 is shown at 25, while in 80 Fig. 5 three such channels are represented, there being actually that number of wheels 1 in the Fig. 5 arrangement, although the middle wheel and parts are omitted in order to show more clearly the channel, and the 85 preliminary or initial track to which reference has already been made and which will be presently explained in full detail. The number of combined displacing or compressing and conveying wheels, that may be 90 employed in connection with a web, depends upon the number and location of channels which it is desired to form therein.

The channel which this mechanism produces has sides that stand approximately at 95 right-angles to the bottom, in contradistinction to sides that are more or less inclined outwardly, so that said channel is quite sharply defined and of a pronounced character, thereby rendering the paper in which 100 the channel is formed most efficient for the purposes for which such paper is intended.

The tracker 6, which is provided when necessary to relieve the wheel 1 of some of its work, consists of a plate that is preferably dished at the bottom so as to present to the pulp 24, in the direction of movement of the latter, a slightly curved surface laterally and a well rounded surface in the other direction, means being afforded for suspending such plate behind said wheel and at an incline downward and forward in the aforesaid direction of movement. The plate of tracker 6, so constructed and when properly adjusted, forms a shallow track 26 in 115 the moving pulp 24, behind and in line with the wheel 1 and just before the latter is reached, such track being concave in cross-section, or deeper in the center than at the edges. In making the track 26 the tracker 120 6 displaces, spreads or disperses the pulp laterally, as said pulp moves along on and with the wire 23, without cutting, gouging, or digging harshly or too abruptly into the soft or plastic mass, to do which would be 125 disastrous. The tracker 6 is somewhat wider than the wheel 1, consequently the track 26 is wider than the channel 25. If the track 26 were only as wide as the wheel 1 or narrower than said wheel, the pulp 130

would be improperly acted on and unevenly or disproportionately channeled upon reaching the wheel.

In the present case the tracker 6 is secured, by means of a long bolt or headed rod 27 and a thumb-nut 28, to an arm 29, and the latter is mounted with the wheel on the sleeve 8. Being mounted on the sleeve 8, the arm 29 and the tracker 6 are adjusted laterally and to and from the wire 23, with the wheel 1, which is a decided advantage, as will be readily seen. The rod 27 passes through a sleeve 30, at the top of the tracker 6, and one end of the arm 29, and the thumb-nut 28 is placed on the part of said rod that protrudes from said arm. Upon tightening the thumb-nut 28 against the arm 29, the head of the rod 27 is forced against the sleeve 30 and the latter against said arm, so that the tracker 6 is held securely in place relative to said arm. The thumb-nut 28 affords an independent adjustment for the tracker, since said tracker, when said thumb-nut is loosened, can be rocked on the rod 27 to locate the base of said tracker nearer to or farther from the wire 23. The end of the arm 29 that is opposite to the bolt 27 is in the form of a split collar 31 which fits on to the sleeve 8, a thumb-nut 32 being provided for the free ends of said collar, with which to bind said collar to said sleeve. Upon loosening the thumb-nut 32 the collar 31 can be adjusted on the sleeve 8 circumferentially, whereby another independent adjustment for the tracker is provided. The tracker is adjusted or set as a rule so that its maximum penetration of the pulp is less than that of the wheel 1.

In practice, the pulp or web 24 travels on and with the Fourdrinier wire 23, in the direction of the associated arrows in Figs. 4 and 5. As the web 24 passes under the trackers 6 the portions of such web that contact with said trackers are dispersed thereby and the shallow concave paths or tracks 26 are produced. Then, as the web continues on its course and the tracks 26 reach and pass under the wheels 1, these prepared portions of said web are formed or converted into the channels 25, by the action of said wheels in displacing or compressing the pulpy material between themselves and the wire 23, and in removing the surplus uncom-pressed particles. The wheels 1 are rotated by the moving web in the direction opposite to that of said web, and in rotating receive and dispose of the surplus pulpy material, discharging the same into the passage 16, with the aid of the buckets 3 and by way of the funnel 5. The channeled portions of the web, in being compressed between the Fourdrinier wire and the wheel, undergo little if any lateral displacement, owing to the fact that what I have termed the surplus material is conveyed away. It is not meant by

this, however, that the stock or material is scraped or scooped out as it were until only the thin bottom of the channel is left, which bottom in that event would be too fragile and weak to hold together, because such is not the case. Enough extra material is pressed into the channel bottom and enters into its formation to render the same strong and serviceable, the channel-forming wheel taking away only enough material to avoid clogging the covering 4, on the one hand, and to prevent piling up the material at the sides of the channel and so producing paper with an uneven surface outside of the channel, on the other hand. When the wheel is properly adjusted relative to the Fourdrinier wire and the pulp thereon, said wheel automatically takes away the required proportion of such pulp, or, it may be said, automatically determines the amount of surplus stock or material to be removed and removes it.

When this mechanism is employed on a Fourdrinier machine, the member or members which both compress, condense or displace and remove portions of the web, and which may be termed combined squeeze and conveyer members or wheels, or combined compressors and conveyers, are located behind the first suction-box in the direction of travel of the pulp-carrying wire.

I am aware that different methods of and means for producing channels in paper have been heretofore employed, such, for example, as by grinding or skiving the finished paper with suitable mechanism, or by employing a rotary member to displace and compress the pulpy material brought into contact therewith, without removing any of such material, however, and extracting by suction moisture from the thin portion, or by treating the web with air pressure, either suction or blast, whereby some of the material is removed entirely or merely displaced by being blown over adjacent portions of the web, and I lay claim to none of these methods or the means for giving them effect.

Necessarily more or less change is required in order to adapt my mechanism to different paper-making machines and for operating on different kinds or grades of plastic material, not only in the shape and size of some or all of the parts, but also in the arrangement and construction thereof, and I do not desire or intend to be restricted to the particular means herein shown and described for obtaining the needed adjustments.

What I claim as my invention, and desire to secure by Letters Patent, is—

1. The method of making paper having a thin portion, which consists in reducing the thickness of the web, to produce such portion, by mechanical pressure and the removal from the web of surplus material

by the rotary action of the pressure-applying means.

2. The method of making paper having a thin portion, which consists in reducing the thickness of the web, to produce such portion, by mechanical pressure and the removal of surplus material by the rotary action of the pressure-applying means and gravity.

10 3. The method of making paper having a thin portion, which consists in reducing the thickness of the web, to produce such portion, by simultaneous mechanical pressure and the removal of surplus material by the 15 rotary action of the pressure-applying means and gravity.

4. The method of making channeled paper consisting in compressing the portion of the web channeled, and at the same time in removing a part of the web portion compressed.

20 5. The method of making channeled paper consisting in compressing by rotary mechanical means the portion of the web channeled, and in utilizing such means to remove a part of the web portion compressed.

25 6. The method of making channeled paper consisting in compressing by rotary mechanical means the portion of the web channeled, and in utilizing such means and gravity to remove a part of the web portion compressed.

30 7. The method of making paper having a thin portion, which consists in initially forming a track in moving pulpy material, and in deepening such track by compression and removal of material.

35 8. The method of making paper having a thin portion, consisting in initially dispersing pulpy material to produce a track therein, which track is deeper at the center than at the portions adjacent to the edges, and in subsequently compressing the portion of material wherein the track is formed to convert such portion into a channel having a bottom the upper and under surfaces of which are approximately parallel.

40 9. The method of making paper having a thin portion, consisting in initially dispersing pulpy material to produce a track therein, which track is deeper at the center than at the portions adjacent to the edges, and in subsequently compressing and partly removing the portion of material wherein the track is formed to convert such portion into a channel having a bottom the upper and under surfaces of which are approximately parallel.

45 10. The method of making paper having a thin portion, which consists in reducing the thickness of the web, to produce such portion, by initial dispersion, and by subsequent mechanical pressure and the removal of surplus material by the rotary action of the 50 pressure-applying means.

11. The method of making paper having a thin portion, which consists in reducing the thickness of the web, to produce such portion, by initial mechanical dispersion, and by subsequent mechanical pressure and the removal of surplus material by the rotary action of the pressure-applying means and gravity.

12. The method of making paper having a thin portion, which consists in reducing the thickness of the web, to produce such portion, by initial mechanical dispersion, and by subsequent simultaneous mechanical pressure and the removal of surplus material by the rotary action of the pressure-applying means and gravity.

13. The method of making channeled paper consisting, first, in dispersing a portion of the web along the course of the channel to be formed, and, second, in compressing and partially removing the remaining portion of the web along such course.

14. The method of making channeled paper consisting in dispersing by stationary mechanical means a portion of the web along the course of the channel to be formed, in compressing by rotary mechanical means the remaining portion of such web along such course, and in utilizing such last-mentioned means to remove a part of said last-mentioned portion during the compressing operation.

15. The combination, in paper-making mechanism, with the pulp-carrying member of a paper-making machine, of means partly to compress and partly to remove from said members simultaneously a portion of the pulpy material on said member.

16. The combination, in paper-making mechanism, with the pulp-carrying member of a paper-making machine, of means partly to compress and partly to remove from said member a portion of the pulpy material on said member, and initial dispersing means behind said first-mentioned means.

17. The combination, in paper-making mechanism, with the pulp-carrying member of a paper-making machine, of means partly to compress and partly to remove from said members simultaneously a portion of the pulpy material on said member, and adjustable means for said first-mentioned means.

18. The combination, in paper-making mechanism, with the pulp-carrying member of a paper-making machine, of initial dispersing means for a portion of the pulp material on said member, means, in advance of said first-mentioned means, to compress and partly remove such portion of material, and adjustable means for said first-mentioned means.

19. The combination, in paper-making mechanism, with the pulp-carrying member of a paper-making machine, of initial dispersing means for a portion of the pulpy

material on said member, means, in advance of said first-mentioned means, to compress and partly remove such portion of material, and adjustable means for said first-mentioned means and said second-mentioned means.

20. The combination, in paper-making mechanism, with the pulp-carrying member of a paper-making machine, of means to form a track in a portion of pulpy material on said member, such tracking being deeper in the center than elsewhere, and means partly to compress and partly to remove the aforesaid portion of material, after it leaves said first-mentioned means.

21. The combination, in paper-making mechanism, with the pulp-carrying member of a paper-making machine, or initial stationary dispersing means for a portion of 20 the pulpy material on said member, and rotary means located in advance of said dispersing means to convert the track made by said dispersing means into a channel.

22. The combination, in paper-making mechanism, with the pulp-carrying member of a paper-making machine, of a stationary initial dispersing member for a portion of the pulpy material on said first-mentioned member, and rotary means, in advance of 30 said dispersing member, to convert the track formed by the dispersing member into a channel.

23. In paper-making mechanism, a tracker plate having a convex pulp-contacting part, 35 and means to support and maintain said plate at an incline relative to the pulp-carrying member of a paper-making machine, and with the bottom edge of said plate a predetermined distance above said member.

40 24. In paper-making mechanism, a tracker plate having a convex pulp-contacting part, means to support and maintain said plate at an incline relative to the pulp-carrying member of a paper-making machine, and 45 with the bottom edge of said plate a predetermined distance above said member, and means to adjust said plate to change such distance.

25. The combination, in paper-making mechanism, with a supporting member, of 50 an arm adjustably mounted on said member, and a tracker plate attached to said arm.

26. The combination, in paper-making mechanism, with a supporting member, of 55 an arm mounted on said member, and a tracker plate adjustably attached to said arm.

27. The combination, in paper-making mechanism, with a supporting member, of 60 an arm adjustably mounted on said member, and a tracker plate adjustably attached to said arm.

28. The combination, in paper-making mechanism, with a supporting member, of 65 an arm mounted on said member, a wire-

covered wheel mounted on said member, and a tracker attached to said arm and extending behind said wheel.

29. The combination, in paper-making mechanism, with a supporting member, of 70 an arm mounted on said member, a wire-covered wheel mounted on said member, and a tracker attached to said arm and extending behind said wheel, the bottom part of said tracker being wider than the periphery 75 of said wheel.

30. In paper-making mechanism, a hollow 80 perforated wire-covered wheel provided with interior buckets, means to mount said wheel in juxtaposition to the pulp-carrying member of a paper-making machine, and a conduit having an open end adjacent to the path of travel of said buckets.

31. In paper-making mechanism, a pulp 85 tracker, a hollow perforated wire-covered wheel, means to mount said tracker and wheel in juxtaposition to the pulp-carrying member of a paper-making machine, and means to adjust said tracker and wheel.

32. In paper-making mechanism, a hollow 90 perforated wire-covered wheel, means to mount said wheel in juxtaposition to the pulp-carrying member of a paper-making machine, and means to adjust said wheel laterally.

95 33. In paper-making mechanism, a pulp tracker, a hollow perforated wire-covered wheel, means to mount said tracker and wheel in juxtaposition to the pulp-carrying member of a paper-making machine, 100 and means to adjust said tracker and wheel laterally.

34. In paper-making mechanism, a pulp tracker, a hollow perforated wire-covered wheel, means to mount said tracker and wheel in juxtaposition to the pulp-carrying member of a paper-making machine, and means to adjust said tracker and wheel to increase or decrease the respective distances 105 between them and said member.

35. In paper-making mechanism, a pulp tracker, a hollow perforated wire-covered wheel, means to mount said tracker and wheel in juxtaposition to the pulp-carrying member of a paper-making machine, means 115 to adjust said tracker and wheel laterally, and means to adjust said tracker and wheel to increase or decrease the respective distances between them and said member.

36. In paper-making mechanism, a hollow 120 perforated wire-covered wheel provided with interior buckets, means to mount said wheel in juxtaposition to the pulp-carrying member of a paper-making machine, means to adjust said wheel, and a conduit having 125 an open end always located adjacent to the path of travel of said buckets.

37. In paper-making mechanism, a hollow 130 perforated wire-covered wheel provided with interior buckets, means to mount said

wheel in juxtaposition to the pulp-carrying member of a paper-making machine, means to adjust said wheel laterally, and a conduit having an open end always located adjacent 5 to the path of travel of said buckets.

38. In paper-making mechanism, a hollow perforated wire-covered wheel provided with interior buckets, means to mount said wheel in juxtaposition to the pulp-carrying 10 member of a paper-making machine, means to adjust said wheel in such a way as to increase or decrease the distance between it and said member, and a conduit having an open end located adjacent to the path of 15 travel of said buckets.

39. In paper-making mechanism, a hollow perforated wire-covered wheel provided with interior buckets, means to mount said wheel in juxtaposition to the pulp-carrying 20 member of a paper-making machine, means to adjust said wheel laterally, means to adjust said wheel in such a way as to increase or decrease the distance between it and said member, and a conduit having an open end 25 always located adjacent to the path of travel of said buckets.

40. The combination, in paper-making mechanism, with the pulp-carrying member of a paper-making machine, of a combined 30 squeeze and conveyer wheel mounted in juxtaposition to said member.

41. The combination, in paper-making mechanism, with the pulp-carrying member of a paper-making machine, of a pulp 35 tracker and a combined compressor and conveyer mounted in juxtaposition to said member.

42. The combination, in paper-making mechanism, with the pulp-carrying member 40 of a paper-making machine, of a pulp tracker and a combined compressor and conveyer both adjustably mounted in juxtaposition to said member.

43. The combination, in paper-making mechanism, of a non-rotary slotted tubular support, a sleeve adjustably mounted on said support, a funnel supported by said sleeve and opening through the slot in said support into the passage therein, and a hollow 50 perforated wire-covered wheel mounted on said sleeve, said wheel being provided with interior buckets which empty into said funnel as said wheel revolves.

44. The combination, in paper-making 55 mechanism, of a non-rotary tubular support,

a sleeve adjustably mounted on said support, a combined squeeze and conveyer wheel mounted to rotate on said sleeve, an arm mounted on said sleeve, and a tracker attached to said arm and located behind said 60 wheel.

45. The combination, in paper-making mechanism, of a non-rotary slotted tubular support, a sleeve adjustably mounted on said support, a funnel supported by said sleeve and opening through the slot in said support into the passage therein, a combined squeeze and conveyer wheel loosely mounted on said sleeve, said wheel having interior buckets which empty into said funnel as 70 said wheel revolves, an arm mounted on said sleeve, and a tracker attached to said arm and located behind said wheel.

46. The combination, in paper-making mechanism, with supporting members, 75 screw-threaded sleeves in said members, bearings having screw-threaded stems arranged for vertical adjustment in said sleeves, and a rod mounted in said bearings, of a combined squeeze and conveyer wheel 80 mounted to rotate on said rod, and a conduit having one end located in operative position relative to said wheel.

47. The combination, in paper-making mechanism, with supporting members, 85 screw-threaded sleeves in said members, bearings having screw-threaded stems arranged for vertical adjustment in said sleeves, and a non-rotary hollow slotted rod mounted in said bearings, of a sleeve adjustably 90 mounted on said rod, a funnel supported by said sleeve and opening through the slot in said rod into the passage therein, and a hollow perforated wire-covered wheel mounted on said sleeve, said wheel being provided 95 with interior buckets which empty into said funnel as said wheel revolves.

48. The combination, in paper-making mechanism, with a supporting rod, and a sleeve on said rod, of a combined squeeze 100 and conveyer wheel mounted to rotate on said sleeve, an arm also mounted on said sleeve, a rod projecting from said arm behind said wheel, and a tracker depending from said rod.

DUNCAN L. McCORKINDALE.
